UNITED STATES PATENT OFFICE.

EDWARD J. BRAUER, OF ST. LOUIS, MISSOURI, ASSIGNOR TO BRAUER BROS., INC., OF ST. LOUIS, MISSOURI, A CORPORATION OF MISSOURI.

GOLF-TEE HOLDER.

Application filed June 3, 1927. Serial No. 196,199.

This invention pertains to holders adapted for holding the wooden golf tees used by many golfers for teeing golf balls.

One of the objects of this invention is to provide means whereby a golfer may carry with him a supply of tees in a convenient manner.

Another object is to provide a tee holder of simple construction and by means of which the tees may be securely held and easily withdrawn.

Another object is to provide such a holder which may be carried on a belt and which may be easily and quickly mounted on the belt or removed therefrom.

Further objects will appear from the following description, taken in connection with the accompanying drawing, in which—

Figure 1 is a perspective view of a ball having a tee holder, embodying this invention, mounted thereon; and

Figure 2 is a view of a tee holder illustrating another embodiment of this invention.

Referring to the drawing, the tees used are usually constructed of wood and comprise a pin 1 which may be inserted in the ground at the point at which the ball is to be teed. At the upper end of the pin is a flaring head 2, having a depression 3 in its upper surface, in which the ball may be set.

The holder comprises a carrier 4, which may be constructed of a strip of leather or other suitable material in the form of a strip, preferably of a width substantially equal to that of the belt upon which it is to be worn. The carrier 4 has formed on each end thereof or attached thereto in any suitable manner an ear 5, having transverse slits 6 through which the belt 7 may be passed, as illustrated in Figure 1. These slits, therefore, provide for supporting the carrier 4 on the belt.

Stitched to the front of the carrier 4, or otherwise suitably attached thereto, is a strip 8 of leather, fabric, or other suitable material. The strip 8 may be stitched to the carrier at spaced points therealong, as illustrated, so as to provide a series of pockets 9 into which the tees may be inserted, as illustrated in Figure 1.

In the embodiment illustrated in Figure 2, the carrier 4 is provided along its upper edge with a series of finger notches 10, one opposite each of the pockets 9, so as to facilitate

removal of a tee from a pocket. On the ends of the carrier 4, a strip 11 of leather or other suitable material is mounted by means of snap fasteners 12. The strip 11 is secured by means of the fasteners 12 to the front of the carrier 4 and passes around in the rear thereof so as to provide a loop corresponding to the slits 6 of Figure 1, through which the belt 7 may be passed to support the carrier.

It will be noted that the slits 6 or the strip 11 provide loops through which the belt may be passed for supporting the holder. In Figure 2, the strip 11 forms an open loop, which may be passed around the belt even while the latter is in place on the person of the player and the end may then be secured by means of the snap fastener 12. This provides for easy attachment of the tee holder to the belt at any time without the necessity of removing the belt to slip the holder off. The loops 11 are provided with snap fasteners at both ends so that either end may be opened and the loop passed around the belt in either direction. The finger notches 10 are positioned to receive the heads of the tees and provide both for securely seating the tees in the pockets and for accessibility thereof for removal. The carrier may be placed in any position on the belt and, after being mounted thereon, may be slid back or forward to any position most convenient to the player.

It is obvious that various changes may be made in the details of construction without departing from the spirit of this invention; it is to be understood, therefore, that this invention is not limited to the specific details shown and described.

Having thus described the invention, what is claimed is:

1. A golf tee holder comprising a strip providing a carrier, means adapted to receive and retain golf tees thereon, a supporting loop for said strip adapted to be passed around a belt, means to fasten one end of said loop adjacent an edge of the strip, and means to detachably fasten the other end of said loop adjacent the other edge of the strip after the loop is passed around a belt.

2. A golf tee holder comprising a strip providing a carrier, a second strip stitched to said carrier at intervals to provide a plurality of pockets adapted to receive and hold golf tees, an open loop at each end of said carrier

adapted to receive a belt, and means to secure the ends of each loop to the front of said carrier thereby to close the loops.

3. A golf tee holder comprising a strip providing a carrier, a second strip stitched to said carrier at intervals to provide a plurality of pockets adapted to receive and hold golf tees, an open loop at each end of said carrier adapted to receive a belt and fasteners on the front of said carrier adapted to detachably engage the ends of each loop, thereby to secure the ends to the front of the carrier and close the loops.

4. A golf tee holder comprising a strip providing a carrier, a plurality of pockets on said carrier adapted to receive and hold golf

tees, finger notches in said carrier opposite said pockets adapted to receive the heads of the tees therein, an open loop on said carrier adapted to receive a belt for supporting the 20 tee holder, and a snap fastener adapted to secure said loop.

5. A golf tee holder comprising a strip providing a carrier, a plurality of pockets on said carrier adapted to receive and hold golf 25 tees, finger notches in said carrier opposite said pockets adapted to receive the heads of the tees therein, and means on said carrier adapted to support the same from a belt.

In testimony whereof I affix my signature 30 this 21 day of April, 1927.

EDWARD J. BRAUER.
